CLAIM

The ornamental design for mouse with receptacle for battery or weight cartridge, as shown and described.

DESCRIPTION

FIG. 1 is an upper perspective view of a mouse with receptacle for battery or weight cartridge showing our new design;

FIG. 2 is a lower perspective view thereof illustrating a receptacle for a battery;

FIG. 3 is a top plan view thereof;

FIG. 4 is a bottom plan view thereof;

FIG. 5 is a front elevational view thereof;

FIG. 6 is a rear elevational view thereof;

FIG. 7 is a left elevational view thereof;

FIG. 8 is a right elevational view thereof; and,

FIG. 9 is a lower perspective view thereof illustrating the receptacle for a weight cartridge.

Phantom lining, where utilized, is for illustrative purposes only, and is not intended to limit the claimed component design to the features shown in phantom.
